ALEXANDER T. KASLEY, OF MOORES, PENNSYLVANIA, ASSIGNOR TO WESTINGHOUSE ELECTRIC & MANUFACTURING COMPANY, A CORPORATION OF PENNSYLVANIA

FEED-WATER HEATER

Application filed October 28, 1927. Serial No. 229,372.

My invention relates to feed water heating systems, and more particularly to systems embodying regenerative heaters, and it has for an object, to improve the efficiency of 5 apparatus of this character.

Where regenerative heaters are used in connection with a steam power installation, the thermal efficiency for the steam which passes through the heaters if, theoretically at 10 least, 100%. Some of the available energy of the steam from the boiler is abstracted in the production of mechanical energy in the prime mover. The steam which is then bled to the feed water heater is condensed to wa- 15 ter at its own temperature, thus giving up its latent heat to the feed water, and the drains from the heater being returned to the feed water, there is, theoretically, no thermal loss.

Moreover, considering the quantity of steam, the size of the apparatus required, etc., it is, as a general proposition, more economical to heat the feed water in successive stages. Such an arrangement requires, either 20 a separate pump between each two of the suc- 25 cessive stages, or one pump which is capable of passing the feed water through all of the various stages.

In the latter case, all of the heaters must 30 be designed to withstand the pressure created by the single pump, which in many cases is as high as 600 pounds per square inch. Ob- 35 viously, this considerably increases the cost of the heaters for the lower pressure stages. On the other hand, where separate pumps are used, there is a saving in the cost of the heaters, but an increased cost due to the ad- 40 ditional pumping apparatus required.

In any event, whether the feed water be 45 heated in several stages, or in a single stage, some form of pumping apparatus has heretofore been required for translating the feed water through the heating system. I have found that it is possible to do away with the various forms of pumping apparatus and to

utilize the energy in the heating fluid, as the bled steam, for translating the feed water.

More particularly, therefore, an object of my invention is to provide a feed water heating system of the type described, which shall 50 embody means for using successive streams of bled steam for translating the feed water in the absence of other means, so far as possible.

Apparatus embodying the features of my 55 invention is shown in the accompanying drawing, forming a part of this specification, and wherein the single figure is an elevation of a steam power installation equipped with a feed water heating system in accordance 60 with my invention, the heaters being shown in section for purposes of illustration.

According to my invention, the heaters are arranged so that the heated fluid may be caused to flow through them by gravity and 65 by the expansive force of the heating fluid. Preferably, the heaters for the lower pressure stages are separated by columns of liquid and liquid seals to balance the pressures between the respective stages. In this way, it is pos- 70 sible to dispense with the use of valves for these stages.

The higher pressure stages are provided with valves which are timed to open inter- 75 mittently and in the proper sequential order to utilize, to the fullest extent, the expansive force of the heating fluid and the force of gravity for passing the heated fluid through the system. Of course, the valves may be omitted altogether and the pressures between 80 all the stages may be balanced by columns of liquid, but as this might require a column several hundred feet high to balance the pressure in the higher pressure stages, I prefer the combined arrangement as outlined above. 85

Referring now to the drawings for a better understanding of my invention, I show a prime mover, such as a bleeder turbine 10, ar- 90 ranged to exhaust to a surface condenser 11, which is provided with a hotwell 12, and with

an extraction pump 13 for removing condensate from the hotwell. The extraction pump 13 is arranged to deliver the condensate through the connection 14 to the feed water heating system.

5 A series of any suitable number of chambers, such as the tanks 16, 17, 18, 19, 20, 21, 22, 23, 24, 25, 26 and 27, are arranged at successively greater elevations so that the condensate may pass by gravity from the connection 14 through these tanks in series. Bleed steam is supplied to the respective tanks through the connections 28, 29, 31, 32, 33, 34, 35, 36, 37, 38, 39 and 40, proceeding from the low-pressure end of the turbine in the order named.

10 Each of the connections 28, 29, and 31 to 40 is provided with a perforated end piece 28', 29', and 31' to 40' respectively. These end pieces extend well into the various tanks and have their inner ends closed, while their respective outer ends are connected to receive motive fluid from the various bleeding connections. By virtue of the perforations and 15 the closed inner ends of these pieces, it is assured that motive fluid will be diffused through the liquid media in each tank and thus, efficiently heat the same. Preferably, these perforated connections are also arranged as near the bottoms of the respective tanks as possible in order to produce maximum heating.

15 In the form of the invention shown, steam is bled through the connections 28, 29, and 31 continuously and, as the pressure differences between these lower stages are relatively small, it is possible to balance the pressures between the tanks 16, 17 and 18 by means of relatively short columns of liquid, such as 20 the feed water, and thus obviate the necessity for valves for controlling the heating in these stages. The tanks 16, 17 and 18 are similar in all respects, with the exception that the tank 18 is made somewhat larger than 25 either the tank 16 or 17 for a purpose to be described later.

20 A circular cup member 41 is disposed within the tank 16 below the depending end of the connection 14, which extends through the upper wall of the tank. The brim of the cup 41 is arranged to project slightly above the lower end of the connection 14 so as to provide a liquid seal to prevent steam, which is passed into this tank through the connection 25 28, from passing into the connection 14.

25 Below the cup 41, and extending transversely across the tank 16, is a spray plate 42, which is provided for causing condensate discharged from the connection 14, and 30 through the liquid seal provided by the cup 41, to be sprayed through the lower portion of the chamber provided by the tank 16, so that it may be heated by steam which passes into this chamber through the connection 28. 35 The tanks 17 and 18 are provided with cup

members 41 and with spray plates 42 for similar purposes.

30 A connection 43 extends from the bottom of the tank 16 into the upper portion of the tank 17 and within the brim of the cup 41. A similar connection 44 extends from the bottom of the tank 17 through the upper portion of the tank 18 and within the brim of the cup 41 in that tank.

35 As the relative difference in pressure of the steam in the connections 28 and 29 will be relatively small, it is possible to balance this difference in pressure by a relatively short connection, such as is provided by the connection 43 between the tanks 16 and 17. 40 The difference in pressure between the connections 29 and 31 would probably be greater, and for this reason the connection 44 between the tanks 17 and 18 is made somewhat longer than the connection 43, so as to provide an adequate column of liquid for balancing this pressure and for assuring proper flow between these stages.

45 It will be obvious that the three stages thus far described may constitute a complete feed water heating system, and that a complete system of this kind may include more or less than three stages as shown, and need not necessarily be supplied only with low-pressure steam, but, of course, if the bleed points are farther apart, or higher pressures are encountered, the respective tanks would be spaced farther apart and the intervening connections, such as the connections 43 and 44 would be lengthened a sufficient amount 50 to provide adequate columns of liquid to compensate for the particular differences in pressure between the respective stages. With relatively high pressures, such columns would attain a considerable height, and for 55 this reason I prefer to use feed heaters of this type only in connection with the lower stages and to provide valves for controlling the flow through the higher pressure stages.

60 Communication between the tanks 18, 19, 20, 21, 22, 23, 24, 25, 26 and 27 is controlled by the magnetic valves 46, 47, 48, 49, 51, 52, 53, 54 and 55 and the passage of the heating fluid, such as bled steam, into the tanks 19 to 27 inclusive is controlled by the magnetic valves 56 to 65, inclusive, which are disposed in the bleeding connections 32 to 40, respectively.

65 In the operation of the apparatus thus far described, condensate from the condenser is supplied, by the extraction pump 13, through the connection 14 into the uppermost tank 16, from whence it may pass by gravity through the tank 17 and into the tank 18. In passing through these tanks it is heated by steam supplied through the connections 28, 29 and 31, respectively.

70 The flow of the feed water through the tanks 19 to 27 is intermittent. Considering only the tank 19, the valve 46 is opened so 75

that this tank may be filled from the tank 18. The valve 46 is then closed, and, the valve 47 remaining closed, the steam valve 56 is opened to admit steam to the tank 19 for heating the feed water therein. After a predetermined heating period has expired, the water valve 47 is opened, and, the steam valve 56 remaining open, the expansion force of the steam is utilized in translating the feed water from the tank 19, through the valve 47, to the tank 20, so that the latter may be filled. The steam valve 56 is closed after the tank 19 is partially emptied. The water valve 47, however does not close until the tank 19 is completely empty, so that all liquid media may drain to the tank 20 where the pressure is very low.

The cycle of operation for each of the tanks 19 to 27 is the same as that just described with reference to the tank 19, but as some of the tanks are empty while others are filled, it will be apparent that the cycle of events occurs simultaneously only in alternate tanks. Considering the operation of the tanks 19 to 27 as a group, it will be observed that the flow from the tank 18 is controlled by the magnetic valve 46, which is opened at the same time that valves 48, 51, 53 and 55 are opened, so that liquid media may pass from the tank 18 to the tank 19, from the tank 20 to the tank 21, from the tank 22 to the tank 23, from the tank 24 to the tank 25, and from the tank 26 to the tank 27. At this time the magnetic valves 47, 49, 52, 54 and 55' are closed. This permits the tanks 19, 21, 23, 25 and 27 to be filled with condensate and, by opening the magnetic valves 56, 58, 61, 63 and 65, bled steam may be supplied for heating.

This being accomplished, the magnetic valves 56, 58, 61, 63 and 65 are closed and the magnetic valves 47, 49, 52, 54 and 55' are opened so as to permit the condensate to pass into the next succeeding of the remaining chambers, namely, the chambers 20, 22, 24, 26 and through the valve 55' to the boiler feed pump. The process is then repeated in these newly filled chambers and, after the heating has been accomplished, the contents are discharged into the next succeeding chambers, and so on, until the feed water has passed completely through the various tanks. Thus it will be seen that steam is bled continuously through the connections 28, 29 and 31, and is bled intermittently through the alternate ones of the connections 32 to 40, inclusive.

It will be obvious, however, that by providing two or more stacks of tanks, such as the stack composed of the tanks 19 to 27, inclusive, the steam may be bled continuously from all the bleed points, should this be considered desirable.

In order to provide for automatically controlling a system of this character, I provide a small motor 70 which, by means of the worm

71, is adapted to rotate the worm wheel 72 and thus, to cause the brush 73, which is carried by the shaft of the worm wheel 72, to rotate in the direction indicated by the arrow, and to wipe against the stationary, arcuate contacts 74, 76, 77 and 78, respectively. Electrical energy is supplied from the positive line 81, through the connection 82, to the brush 73 in any suitable manner, as by means of slip-rings or the like (not shown). The motor 70 may also be supplied with electrical energy from the positive line 81 through the connection 83, and may be connected with the negative line 84 through the connection 86.

The magnetic valves 46, 48, 51, 53 and 55 are arranged in parallel between the connection 87, from the arcuate contact 77, and the connection 88 to the negative line 84. Hence, these valves are opened while the brush 73 completes the circuit through the arcuate contact 77.

Likewise, the magnetic valves 47, 49, 52, 54, and 55' are in parallel between the connection 89, from the arcuate contact 76, and the connection 91 to the negative line 84. Similarly, the magnetic valves 56, 58, 61, 63 and 65 are in parallel between the connection 92, from the arcuate contact 74, and the connection 93 to the negative line 84. The magnetic valves 57, 59, 62 and 64 are arranged in a like manner between the arcuate contact 78 and the negative line 84 by means of the connections 94 and 96, respectively.

It will be obvious, therefore, that the respective valves in these various groups will only be opened when the brush 73 completes the circuit through that stationary, arcuate contact which is associated with each group of valves.

With the motor 70 operating at a constant speed, the length of the stationary contacts determines the time that the various valves may remain open, and it will be observed that the contacts 74 and 78 are symmetrically arranged and are of greater length than the contacts 76 and 77, which are likewise symmetrically disposed.

It will also be observed that the rotating brush 73 will complete the circuit through the steam valves controlled by the contact 74 before the circuit is made through the contact 76, and that the water valves controlled by the contact 76 will remain open after the steam valves controlled by the contact 74 have been closed.

The purpose of this arrangement is to admit steam to the filled tanks for a definite heating period, then to open the water valves to allow these tanks to drain into the next succeeding tanks and to continue passing steam into the tanks, where the heating has just taken place, for the purpose of accelerating the discharge of liquid media from such tanks. In this way, it is possible to utilize the expansive force of successive streams of

bled steam for translating the feed water through the system and while, of course, this feed water would tend to gravitate of its own accord from one tank to another if permitted to do so, it will be clear that the process is considerably hastened by virtue of the expansive force of the steam.

The steam valves controlled by the contact 74 are closed before the water valves which are controlled by the contact 76. Hence, it is assured that no pressure will be built up, in any of the tanks, which would tend in any way to interfere with the flow of condensate therethrough.

Inasmuch as the contacts 77 and 78 are arranged in a manner similar to those just described, it will readily be seen that the steam valves controlled by the contact 78, and the water valves controlled by the contacts 77 will operate in a manner similar to that just described with reference to the contacts 74 and 76.

With the brush 73 in substantially the position indicated, the tanks 19, 21, 23, 25 and 27 would be filled while the remaining tanks would be empty, with the exception of tank 18, in which, it will be remembered, water is continuously admitted and which is made larger than the other tanks for permitting this water to accumulate in order to compensate for the intermittent operation of the magnetic valve 46.

It will thus be seen that I have provided a system for utilizing the force of gravity, either alone, or in combination with the expansive force of successive streams of bled steam for translating feed water through a series of feed water heaters and thus, it is possible to dispense with the various forms of pumping apparatus which have heretofore been required for this purpose.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. A feed water heating system comprising a plurality of communicating chambers arranged at progressively greater elevations, valve means for controlling the flow between said chambers, a passage for conducting heating fluid under a relatively low pressure to the uppermost of said chambers, independent passages for conducting heating fluid to successive chambers at successively greater pressures, other valve means for controlling the flow through each of said passages, and control means for operating the various valve means for periodically admitting heating fluid to alternate chambers and for releasing

liquid media from the respective alternate chambers to the respective succeeding chambers during the admission of heating fluid to the respective alternate chambers.

2. In a feed-water heating system, the combination of a plurality of chambers arranged successively at greater elevations, said chambers including an upper group and a lower group, means for supplying water continuously to the uppermost chamber of the upper group and from the latter in succession to the remaining chambers of the upper group, means for continuously supplying steam at a range of low pressures to the chambers of the upper group, the steam being supplied to the chambers of the upper group considered downwardly and successively at successively greater temperatures and pressures and the chambers of the upper group being spaced apart successively distances such that the barometric column between chambers counterbalances or compensates for the greater pressure of steam entering a following chamber, means providing for the passage of water from the lowermost chamber of the upper group downwardly and intermittently through the chambers of the lower group, means for supplying steam to the chambers of the lower group considered downwardly and successively at successively higher temperatures and pressures after the latter chambers are filled and during at least the first portions of the periods of discharge therefrom.

3. In a feed-water heating system, the combination of a plurality of chambers arranged successively at greater elevations, said chambers including an upper group and a lower group, means for supplying water continuously to the uppermost chamber of the upper group and from the latter in succession to the remaining chambers of the upper group, means for continuously supplying steam at a range of low pressures to the chambers of the upper group, the steam being supplied to the chambers of the upper group considered downwardly and successively at successively greater temperatures and pressures and the chambers of the upper group being spaced apart successively distances such that the barometric column between chambers counterbalances or compensates for the greater pressure of steam entering a following chamber, a passage for connecting the lower portion of the lowermost chamber of the upper group to the upper portion of the uppermost chamber of the lower group, passages for connecting the chambers of the lower group in series, each of such connecting passages communicating with the lower portion of a preceding chamber and with the upper portion of the succeeding chamber, a discharge passage communicating with the lower portion of the lowermost chamber, valves in all of said passages, operating

means for said valves constructed and arranged to provide for the intermittent passage of water from chamber to chamber in the chambers of the lower group and the discharge of water from the lowermost chamber of that group, conduits for supplying steam to the chambers of the lower group considered downwardly and successively at successively higher temperatures and pressures, valves for the conduits, and controlling means for the conduit valves providing for the admission of steam to the chambers of the lower group after they are filled from preceding chambers and during at least the first portions of discharge therefrom.

4. In a feed-water heating system, the combination of a plurality of chambers arranged at successively higher elevations, means for supplying water to the uppermost chamber, means providing for the intermittent passage of water downwardly through the following chambers, means for supplying heating medium to the uppermost chamber, and means for intermittently supplying heating medium to said following chambers after the latter are filled with water and during at least the first portions of the periods of discharge therefrom and for alternately interrupting the supply of heating medium when said chambers are being filled with water, said heating medium supply means supplying heating medium to downwardly successive chambers at successively higher temperatures.

5. In a feed-water heating system, the combination of a plurality of chambers arranged at successively higher elevations, means providing for the intermittent passage of water downwardly through the chambers, means for intermittently supplying heating medium to the chambers after the latter are filled with water and during at least the first portions of the periods of discharge therefrom and for alternately interrupting the supply of heating medium when said chambers are being filled with water, said heating medium supply means supplying heating medium to downwardly successive chambers at successively higher temperatures.

6. In a feed-water heating system, the combination of a plurality of chambers arranged in superposed substantially vertical relation, means for supplying water to the upper chamber, passages for connecting the chambers in series, an outlet passage for the lowermost chamber, valves arranged in said passages, means for operating the valves so that water is passed through the chambers intermittently from chamber to chamber, conduits for supplying heating medium to the chambers, said conduits being arranged to supply heating medium to downwardly successive chambers at successively higher temperatures, valves in all of said

conduits except the conduit supplying the uppermost chamber, and means for controlling the operation of the conduit valves so that steam is admitted to the chambers after being filled with water from preceding chambers and during at least the first portions of discharge therefrom.

In testimony whereof, I have hereunto subscribed my name this 17th day of October, 1927.
